UNITED STATES PATENT OFFICE.

WILLIAM MATHEW PRICHARD, OF COOLEDGE, TEXAS.

ATTACHMENT FOR HULLER-GINS.

1,273,182.

Specification of Letters Patent. Patented July 23, 1913.

Application filed February 12, 1913. Serial No. 216,712.

To all whom it may concern:

Be it known that I, WILLIAM MATHEW PRICHARD, a citizen of the United States, residing at Cooledge, in the county of Limestone and State of Texas, have invented certain new and useful Improvements in Attachments for Huller-Gins, of which the following is a specification.

My invention relates to improvements in cotton gins and in such connection it has particular reference to an attachment for that type of cotton gin known as the huller gin wherein the cotton is positively fed or forced to or upon the gin saws prior to its entrance to the roll box. My invention also has reference to the construction, arrangement and location of such an attachment.

In the operation of cotton gins as now constructed considerable difficulty is experienced in properly feeding the gin and in conducting the cotton after hulling into the roll box. This difficulty is experienced particularly where hulky cotton is being ginned, as the gins are constantly choked up, the cotton is not properly freed of its hulls and does not on that account enter the roll box, necessitating constant supervision of each gin, loss of time in cleaning out the gins, and additional labor for running the gin stand.

The usual construction of the ordinary huller gin calls for gin saws and lint removing means in connection with the roll box, the ribs and a picker roll arranged at the base or bottom of the inlet to the gin. The cotton under force of gravity falls upon the picker roll, its hulls are thereby broken and removed from the cotton and the cotton at the same time is drawn by the saws through the huller ribs into the roll box. There is no arrangement or attachment for positively feeding or forcing the cotton to these saws and if the cotton is hulky the hulls accumulate and prevent the cotton from reaching the saws in front of the huller ribs.

My invention provides a means for forcing the hulky cotton to the saws immediately in front of the huller ribs which means consists of a shaft upon which are mounted a plurality of pins in a somewhat spiral formation. The shaft is channeled or cut away in spiral form, the spiral channeling, thus formed, separating the pins on the shaft.

This shaft cooperates with the saws in the drawing of the cotton by the saws through

the ribs into the roll box and also cooperates with the picker roll in drawing the hulls out of the cotton and discharging same from the gin.

The operation and construction of my invention will be more fully understood from the following description taken in connection with the accompanying drawings forming part hereof, in which:

Fig. 1 is a cross sectional view taken through a huller gin of the usual type showing my invention embodied therein.

Fig. 2 is a side view of the shaft showing the arrangement of the pins and the channel or groove of the shaft.

Fig. 3 is a plan view showing the continuation of the pin arrangement and grooves around the shaft.

Fig. 4 is a view taken from the opposite side of Fig. 2, and

Fig. 5 is an end elevational view.

Referring more particularly to the drawings 1 represents the inlet to a huller gin, 2 the roll box, 3 the saws, 4 the brush for removing lint from the saws, 5 represents the seed ribs and 6 the huller ribs which are all of well known construction and arrangement. 7 is the discharge opening of the inlet 1 wherein is arranged a picker roll 8 the teeth or pins 9 of which are arranged slightly tangential to the periphery of the roll.

The roll 8 in revolving presents the back or obtuse angled portion of the pins 9 to the saws 3 and the pins traverse the hulky cotton with a combing like movement to draw out the hulls from the fiber and discharge same through outlet 7.

Between the roll box 2 and the picker roll 8 and in the throat 1 in front of saws 3 and huller ribs 6 is arranged a shaft 10 having the pins 11 mounted on the periphery or spiral ridges 12. 13 represents the depression or groove, between the pins 11, this groove 13 extending spirally around the shaft. In the revolution of the shaft 10 each of the pins 11 will cooperate successively with a set of two adjacent saws of the saw cylinder. In its revolution the shaft 10 presents the points or ends of the pins 11 to the saws 3 and also to the pins 9 of the picker roll 8, the picker roll revolving in the same direction as the shaft 10.

The pins 11 of the shaft 10 enter the hulky cotton with a combing action and present or feed the fiber forcibly to the saws. The

pins also separate the hulls from the cotton and drag these hulls into operative position with respect to the pins 8 of the picker roll 7. The spiral groove of shaft 10 permits the hulky cotton to travel with the shaft in the presentation of the entire hulky cotton to the ribs 6 before the hulls reach the picker roll 8.

Having thus described the nature and objects of my invention what I claim as new and desire to secure by Letters Patent, is—

In a huller gin, in combination with the

roll box, the saws, the ribs and a picker roll, of a revoluble shaft with spiral grooves having pins mounted on the ridges between 15 the grooves at right angles to the periphery of the shaft, said shaft arranged adjacent to the saws and between the roll box and picker roll and said pins presenting their points to the saws during the rotation of 20 said shaft.

In testimony whereof I have signed my name to this specification.

WILLIAM MATHEW PRICHARD.
